D. ZAKIM.

LEAD PENCIL.

APPLICATION FILED MAY 31, 1921.

Patented Aug. 22, 1922.

Inventor
DAVID ZAKIM

By his Attorney

Charles G. Gile

UNITED STATES PATENT OFFICE.

DAVID ZAKIM, OF NEW YORK, N. Y., ASSIGNOR TO STERLING METAL NOVELTY M'F'G CO., INC., OF NEW YORK, N. Y., A CORPORATION OF NEW YORK.

LEAD PENCIL.

1,426,438.

Specification of Letters Patent. Patented Aug. 22, 1922.

Application filed May 31, 1921. Serial No. 473,599.

To all whom it may concern:

Be it known that I, DAVID ZAKIM, a citizen of Poland, and a resident of Bronx, in the county of Bronx and State of New York, 5 have invented certain new and useful Improvements in Lead Pencils, of which the following is a specification.

The invention relates to improvements in mechanical lead pencils of the clutch type, 10 and it resides in certain novel features hereinafter described whereby within the barrel of a clutch pencil I provide a reservoir for leads to be used with the pencil. Mechanical pencils of the plunger type have been 15 equipped with chambers for holding reserve leads, but I am not aware that a clutch pencil has been so constructed as to provide a reservoir or chamber for reserve leads, and my invention is confined to means for forming within the barrel of a clutch pencil, exterior to the clutch tube, an adequate chamber for holding reserve leads.

The clutch pencil of my invention comprises an exterior tubular barrel tapered at 25 its forward end to form a tip member, a clutch tube within said barrel, a head carrying said clutch tube and threaded to engage a projection or thread within the rear end of said barrel and a tubular member located 30 within said barrel and exterior to and encompassing the clutch tube, said tubular member permitting of a free sliding movement of the clutch tube through it and having at its ends laterally extending means for 35 engaging the inner wall of the exterior barrel and forming a chamber between itself and the exterior barrel for receiving a reserve stock of leads.

The invention will be fully understood 40 from the detailed description hereinafter presented, reference being had to the accompanying drawings, in which:

Fig. 1 is a central longitudinal section through a clutch pencil constructed in accordance with and embodying my invention;

Fig. 2 is a perspective view of the tubular member provided by me for insertion within the exterior barrel of the pencil and forming with said barrel the reservoir for reserve 50 leads;

Fig. 3 is a transverse section through the lead pencil, taken on the dotted line 3—3 of Fig. 1;

Fig. 4 is a similar section through the

same, taken on the dotted line 4—4 of Fig. 55 1, and

Fig. 5 is a corresponding section, taken on the dotted line 5—5 of Fig. 1.

In the drawings, 10 designates the exterior tubular barrel or casing of the pencil, 60 11 a tapered tip-member formed on the forward end of said barrel, 12 the clutch tube, and 13 a head to which said clutch-tube is secured and which is formed with a nut 14 to enter the rear end of the barrel 10 and 65 whose thread is adapted to engage an inwardly pressed lug 15 formed on the barrel 10. The rear end of the clutch-tube 12 is secured in a socket within the nut 14 in the usual manner, and the exposed portion of 70 the head 13 will be of any suitable ornamental character. The thread on the nut 14 is adapted to engage the lug 15, and said lug avoids the provision of a regular screw thread on the interior of the barrel 10. The 75 nut 14 and clutch-tube 12 operate in their usual manner, and said clutch-tube at its forward end is slotted on opposite sides, as at 16, to receive the lead 17 and operate to clutch said lead when, by means of the 80 head 13, the clutch-tube is forced forwardly so that the members of its forward end become pressed against the inner walls of the tapered tip-member 11 of the barrel or casing 10, this being the usual operation of 85 clutch pencils. In accordance with my construction the slots 16 of the clutch-tube 12 terminate within the forward portion of the barrel or casing 10, and hence the tube 12 from the inner ends of the slots 16 to the 90 nut 14 present integral smooth unbroken surfaces.

In accordance with my invention I insert into the outer casing or barrel 10 the reservoir-forming member 18 separately illustrated in Fig. 2 and consisting of a tube 19 having at one end a head 20 and at the other end three radial arms 21 whose outer ends are bent forwardly, as at 22. The head 20 may be in the form of a cup or the like, as 100 shown, and said head is fastened to the tube 19 and very snugly fits within the barrel or casing 10, as shown in Fig. 1. The head 20 may take various forms, but I prefer to make the same of sheet metal and of 105 cup form and to give the same such proportions as will insure, by the fit of the head within the barrel 10, the remaining station-

ary of the member 18 after said member has been introduced to position within said barrel. The arms 21 I form from the material of the tube 18 by slitting the end of the tube 5 and bending the slitted members outwardly to form the arms 21 and forwardly extending arms 22. The arms 22 also tightly fit within the exterior casing or barrel 10 and aid in maintaining the member 18 stationary 10 and properly spaced from the inner walls of said casing. The tube 19 is of a diameter to snugly receive the clutch tube 12 and to permit said tube to have its usual movements forwardly and backwardly in the customary 15 manipulation of a clutch pencil. The tube 19 is beneficial in its relation to the clutch tube 12 in that it serves as a guide for said tube 12 and helps to maintain the same concentrically within the exterior casing or 20 barrel 10. I provide the tube 19 more especially for the purpose of forming between itself and the inner walls of the exterior casing or barrel 10 a chamber 23 to serve as a reservoir for reservoir leads, 25 which I number 24. The arms 21 space the tube 19 at its rear end from the inner walls of the barrel 10 and leave entrance spaces, 30 as shown in Fig. 3, for the passage of the leads 24 into the chamber 23. The inner ends of the leads 24 find a bearing against the head 20 which serves as a support for the leads and prevents the leads from slipping downwardly into the tip member 11 of the exterior casing, or in other words the head 35 20 serves as the bottom wall of the chamber 23 and as a support for the leads 24 during the use of the pencil. The arms 21 by being widely spaced apart, as shown in Fig. 3, form entrance spaces for the leads 24, and 40 also as means for guiding the clutch end of the tube 12 to the tube 19, through which said tube 12 is passed on being introduced to its position shown in Fig. 1.

When leads are to be introduced to the 45 chamber 23 the head 13 and tube 12 are withdrawn from the exterior casing or barrel 10, and after the leads 24 have been inserted between the arms 21 and into the chamber 23, said head and tube 12 are re- 50 stored to position, the leads 24 then being confined within the chamber 23 and between the head 20 and the nut 14 carried by said head, as represented in Fig. 1. The reservoir forming member 18 keeps the leads 55 24 separated from the tube 12 or from in any manner interfering with the operation of said tube. The member 18 is comparatively inexpensive to manufacture and converts the clutch pencil into a reservoir pen- 60 cil adapted for holding a reserve stock of leads.

I do not limit my invention to all of the 65 details of form and construction hereinbefore described for carrying out my invention, but I recommend the construction

shown in Fig. 2 since it is one which has proven to be of practical merit.

What I claim as my invention and desire to secure by Letters Patent, is:

1. A clutch pencil comprising an exterior 70 tubular casing formed integrally therewith with a forward tapered tip-member, a central clutch tube extending longitudinally through said casing and adapted at its forward end to said tip-member, and at its rear 75 end having rigidly secured thereto an exposed head carrying a nut in threaded engagement with the rear end of said exterior casing, said head closing the rear end of said casing and being detachable with said tube 80 from said end of said casing, and an elongated tube through which said clutch-tube extends and by which it is guided in its longitudinal movement in which elongated tube has on its forward end a cup-shaped head closely engaging at its sides the interior walls of said casing and serving to position said elongated tube, said head also serving as a support for reserve leads introduced through the rear end of said casing 90 into the chamber left between said elongated tube and said casing.

2. A clutch pencil comprising an exterior tubular casing formed integrally therewith with a forward tapered tip-member, a central clutch tube extending longitudinally 95 through said casing and adapted at its forward end to said tip-member, and at its rear end having rigidly secured thereto an exposed head carrying a nut in threaded engagement with the rear end of said exterior casing, said head closing the rear end of said casing and being detachable with said tube 100 from said end of said casing, and an elongated tube through which said clutch-tube 105 extends and by which it is guided in its longitudinal movements and which elongated tube has at its forward end a laterally extending head closely engaging the interior walls of said casing and at its rear end laterally extending spaced-apart arms closely engaging said walls, a chamber for reserve leads being formed between said elongated tube and said casing and said leads being introducible into said chamber through the 110 rear end of said casing and between said spaced-apart arms, and said head serving as a support for said leads.

3. A clutch pencil comprising an exterior tubular casing formed integrally therewith 120 with a forward tapered tip-member, a central clutch tube extending longitudinally through said casing and adapted at its forward end to said tip-member, and at its rear end having rigidly secured thereto an exposed head carrying a nut in threaded engagement with the rear end of said exterior casing, said head closing the rear end of said casing and being detachable with said tube 125 from said end of said casing, and an 130

elongated tube through which said clutch-
tube extends and by which it is guided in its
longitudinal movements and which elong-
ated tube has at its forward end a laterally
extending cup-shaped head closely engaging
the interior walls of said casing and at its
rear end laterally extending spaced-apart
arms whose extremities are bent longitudi-
nally to engage the inner walls of said cas-
ing, a chamber for reserve leads being

formed between said elongated tube and said
casing and said leads being introducible into
said chamber through the rear end of said
casing and between said spaced-apart arms,
and said head serving as a support for said 15
leads.

Signed at New York city, in the county
of New York and State of New York, this
27th day of May A. D., 1921.

DAVID ZAKIM.
